SPEED CHANGING MECHANISM FOR COTTON GIN FEEDERS AND THE LIKE

Hugh Roberts, Jr., Columbus, Ga., assignor to
Cen-Tennial Cotton Gin Co., Columbus, Ga.,
a corporation of Georgia

Application July 23, 1935, Serial No. 32,796

4 Claims. (Cl. 74—351)

This invention relates to improvements in change speed mechanism, and is more particularly advantageously employed with devices of the nature of cotton gins where it is necessary to have a simple and easily operated device that is not readily susceptible of derangement.

One of the features of the present invention is the provision of a change speed gearing employing a selectively positioned gear, and means for selecting and holding the gear in position for the particular speed desired.

Another feature of the present invention is the provision of gearing including a selecting gear and means for positioning the same in and out of engagement with a second gear member, in conjunction with means for latching the gear against movement toward or from another position of speed selection.

A further feature of the present invention is the provision of a change speed gearing including a gear which is movable in one direction for disengagement from another gear member and movable in a second direction to prepare it for a change of speed, in association with means for holding the gear latched when in engagement and in a position of nonengagement with the gear member.

With these and other features as objects in view, an illustrative form of practicing the invention is shown on the accompanying drawings, in which:

Figure 1 is an end elevation of a cotton gin feeder, with the present invention applied thereto.

Figure 2 is a side view, with parts broken away, of the change speed mechanism on a large scale.

Figure 3 is a face view of the same.

Figure 4 is a view on the axis of the spline shaft.

Figures 5, 6 and 7 are sectional views substantially on line 5—5 of Fig. 2, showing the mechanism in three different positions.

Figures 8 and 9 are perspective views on a larger scale respectively of the slider member and of the double cam.

In these drawings, the cotton gin feeder is illustrated as having a general housing 10 provided with a top feed opening 11, a discharge chute 12, and shafts 13 connected to cleaning, stripping and conveying devices located within the housing; since such devices are well known in the art, they are not more closely identified herein. These shafts are connected by belts 14 and 15 which pass over appropriately sized pulleys 16.

In the illustrated form of the present invention, 55 a shaft 13a for a cleaning roll extends through

the end of the housing (Figs. 1, 3 and 4) and is provided with a worm 20 located within a casing 21 which is secured to the end wall of the housing 10. The illustrative form in Fig. 1 shows that a belt and pulley drive 17 (located at the other end of the feeder) establishes a driving connection between the shaft 13a and another shaft 13 of the driven system.

As shown in Fig. 4, the worm 20 meshes with a worm wheel 22 which is secured to a spline shaft 23. This spline shaft is preferably provided with a universal joint 24. The lower end of the spline shaft 23, in Fig. 4, is carried by a bearing block 25 which is held within the casing 21 by a screw 26.

The spline shaft 23 receives a driving pinion 30 having teeth which engage in apertures in a driven grid plate 31. This driven plate is illustrated in Figs. 2 and 3 as having six rows of concentric rows of such apertures, each having a different number of apertures from the others. This driven plate 31 is fixed on a shaft 32 which illustratively is assumed to be connected to a feeding roller (not shown) of the cotton gin feeder.

A stirrup piece 33 has apertured arms 34 which fit around the spline shaft 23 and are spaced a distance closely approximating the length of the pinion 30, so that movement of the stirrup produces movement of the pinion axially of the spline shaft 23, the key 35 being likewise detained 30 and held within the pinion and engaged with a keyway in the spline shaft 23, so that the shaft compels rotation of the pinion.

The stirrup 33 supports two bolts 36 which extend through a web 37 of a slider member 38 which has eyes fitting around the two guide rods 39 which themselves are supported fixedly by a bracket 40 mounted on the end of housing 10 and in a bracket extension piece 41 which is connected to the bracket 40 by a strong back 40 member 42.

The bolts 36 have heads for compressing springs 43 against the web 37 when the stirrup is moved to engaged position (Fig. 5).

An adjusting shaft 45 has an operating knob 46 at its lower end and extends slidably through an eye 21a of the casing 21, and may also slide in apertures provided in the bracket 40 and the extension piece 41.

Fixed to this adjusting shaft 45 is a double cam member having a pair of curved noses 47 for engaging the stirrup 33, and also including a pair of latching noses 48 for engaging between the teeth 49 of the strong back member 42. It is preferred to have the latching noses 48 formed 55

with bevels 48a at their ends for guiding the parts into proper alignment before the pinion 30 is moved into engagement with the driven plate 31.

- 5 The operation of the structure is as follows: As shown in Figs. 2 and 3, the pinion 30 is engaged with the second row of apertures from the outer edge of the disk, corresponding to the second slowest speed. The adjusting shaft 45 and its double cam is presenting flattened ends of the cam noses 47 against the stirrups 33; the double cam is detained against further counterclockwise movement by projections 33a of the stirrup 33; and the pinion 30 is held fixedly in engagement. The springs 43 are compressed, and their extension is prevented by the flat on the ends of the cam noses 47. The drive is proceeding to the shaft 13a and thence by worm 20 and wormwheel 22 to the spline shaft 23, and through the universal 24 to pinion 30, and thus to the driven plate 31.

If it be desired to interrupt the driving of the shaft 32, the knob 46 is given a partial rotation in a clockwise direction, so that the springs 43 operate to draw the stirrup 33 and therewith the pinion 30 away from the driven plate 31, so that the meshing engagement is interrupted and the spline shaft 23 continues to rotate, but the driven plate 31 is no longer actuated. This operation results in a movement of the axis of the upper part of the spline shaft 23, as permitted by the universal joint 24.

Re-engagement may be effected by turning the knob 46 in a counterclockwise direction so that the noses 47 force the stirrups 33 toward the left from the position of Fig. 6 into that of Fig. 5. A tooth of the pinion 30 soon engages an aperture in the driven plate 31, and the movement may be completed so that the parts regain the position of Fig. 5.

When it is desired to change the speed of drive, the parts are brought to the position of Fig. 6, if not already therein, and further clockwise movement is then given to the knob 46, so that the latching noses 48 are moved out of engagement with the rack teeth 49 (Fig. 7), and then an endwise sliding movement is given the knob 46, so that the shaft 45 moves axially. At this time, the stirrup 33 has its projections 33a fitting over the web 37, and the shaft transmits its movement directly to the double cam and thence to the sliding member 38 and to the stirrup 33, so that the latter causes an axial movement of the pinion 30 along the spline shaft 23 into a desired position. When the pinion 30 is opposite the desired row of apertures in the driven plate 31, the knob 46 is given a counterclockwise movement from the position of Fig. 7 into that of Fig. 6. During this movement, the beveled ends 48a of the latching noses 48 enter into the spaces between adjacent teeth and operate to guide the double cam into a proper position in the axial direction of the spline shaft 23 and thus to present the pinion 30 at a proper radial position with respect to the driven plate 31 for accurate re-engagement. The transmission of power is then effected by continuing the movement of the knob 46 to restore the parts to the position of Fig. 5.

It is obvious that the invention is not limited solely to the form of construction shown, but

that it may be modified in many ways within the scope of the appended claims.

I claim:

1. A change speed mechanism comprising a driving shaft rockable in an axial plane, a pinion compelled to rotate with but slideable along said shaft, a driven structure including a plurality of rows of members for selective meshing engagement with said pinion, an adjusting shaft substantially parallel to said driving shaft, a plurality of fixed latching teeth located adjacent said adjusting shaft, and a cam device fixed to said adjusting shaft and engageable and disengageable from said teeth, said device also including means for introducing said pinion into mesh with one said row while the device is engaging corresponding said teeth.

2. A change speed mechanism comprising a first shaft, a pinion compelled to rotate with but slideable along said shaft, a rotatable structure including a plurality of rows of members for selective meshing engagement by said pinion, an adjusting shaft, first means connected to move axially with said adjusting shaft for shifting said pinion axially along said first shaft, second means connected for movement when the adjusting shaft is rotated for causing the pinion to mesh with or leave a selected row of members, and devices also connected for movement when the adjusting shaft is rotated for securing the pinion against axial movement when in mesh with a row of said members.

3. A change speed mechanism comprising a frame, a shaft, a pinion compelled to rotate with but slideable along said shaft, a rotatable structure including a plurality of rows of members for selective meshing engagement by said pinion, a spring normally tending to effect meshing of the pinion and a row of members, means for compressing said spring to disengage said pinion from said members, means for sliding the pinion from position opposite one row to a position opposite another row, means for holding said pinion in alignment with a selected row of members comprising devices on the frame and on said sliding means, and interconnecting devices between said compressing and holding means for preventing release of the compressed spring when the pinion is not in alignment with a row of members.

4. A chain speed mechanism comprising a spline shaft, a pinion for rotation but slideable along said spline shaft, a slideable structure including a plurality of rows of members for selective meshing engagement by said pinion, a stirrup piece embracing the spline shaft and operative for determining the position of the pinion thereon, a slider member, means connecting the stirrup piece and slider member so that they move axially together, a rotatable member, a double cam member secured to said rotatable member and having a cam nose for effecting movement of said stirrup piece to effect meshing and disengagement of said pinion from said rotatable structure and also having another cam nose, and fixed devices cooperative with said other cam nose for latching said rotatable and slider members and stirrup piece against axial movement of the pinion.
